(57) **CLAIM**

The ornamental design for a pour spout, as shown and described.

DESCRIPTION

FIG. 1 is a top perspective view of a pour spout showing our new design;

FIG. 2 is a side perspective view thereof;

FIG. 3 is a top plan view thereof;

FIG. 4 is a bottom plan view thereof;

FIG. 5 is a side view thereof; and,

FIG. 6 is a cutaway side view thereof taken through plane A-A in FIG. 4.

The broken lines shown in the drawings are included for the purpose of illustrating environmental structure and form no part of the claimed design.
